UNITED STATES PATENT OFFICE.

RALPH C. SEYMOUR, OF SHORT HILLS, NEW JERSEY.

PRINTING PRESS.

Application filed August 30, 1923, Serial No. 660,141. Renewed January 24, 1928.

- The invention relates to printing presses and more especially to novel features applied to the inking mechanism of rotary presses.
- 5 Objects and advantages of the invention will be set forth in part hereinafter and in part will be obvious herefrom, or may be learned by practice with the invention, the same being realized and attained by means 10 of the instrumentalities and combinations pointed out in the appended claims.
- The invention consists in the novel parts, constructions, arrangements, combinations and improvements herein shown and described.
- 15 The accompanying drawings, referred to herein and constituting a part hereof, illustrate one embodiment of the invention, and together with the description, serve to explain the principles of the invention.
- 20 Fig. 1 is a fragmentary elevation of a printing press embodying the invention and showing the inking mechanism away from the form cylinder.
- 25 Fig. 2 is a view similar to Fig. 1 but showing the inking mechanism in operative position with respect to the form cylinder;
- Fig. 3 is a fragmentary, enlarged section through one of the locking devices;
- 30 Fig. 4 is a vertical section on line 4-4 of Fig. 3, looking in the direction of the arrows.
- The invention is shown applied to a rotary printing press having a slidable inking mechanism carriage, the general features of which are an old and well-known form, the present invention being especially directed to providing a novel, but simple and highly efficient, locking means for firmly and accurately locking the inking mechanism in operative relation with respect to its form cylinder. Among the advantages of my improved locking mechanism are that it locks 40 equally on both sides, but is operable from one side of the press so as to simultaneously lock both sides, and likewise to unlock both sides, in a very easy, rapid and efficient manner. Other objects and advantages of the invention will be first mentioned in connection with the following detailed description of the present preferred embodiment.
- 45 The general frame 1 of a printing press is shown fragmentarily in the drawings, and a form or plate cylinder 2 is journaled therein. The form cylinder is suitably mounted in the press frame and this mounting is
- shown more or less diagrammatically and with parts omitted, as it constitutes no part of the present invention. A journal box 3 for the end of the cylinder shaft 4 is mounted 60 in the machine frame, and an eccentric throw-off bearing 5 is also shown, and as stated these may be of any convenient or desired form, so far as concerns the present invention.
- 65 The inking mechanism is of the sliding carriage type, and in its entirety is movable to and from the form cylinder to give access to the cylinder for changing plates, making ready or for other purpose. The 70 inking mechanism carriage has a base 10, mounted on the base 11 of the printing press frame, movable on roller bearings arranged between 10 and 11, on either side of bar 12.
- 75 The inking mechanism carriage is moved to and from operative relation with the form cylinder by any suitable means, such as a rack and pinion mechanism of any suitable or convenient form, the hand wheel 13 of 80 which is shown in Figs. 1 and 2.
- The inking mechanism may likewise be of any suitable or convenient form, and as shown, an ink fountain 14 is mounted upon the carriage. Form inking rollers 15 are 85 shown at the opposite side of the carriage, and in Fig. 2 these are shown in operative relation with the plates upon the form cylinders. The other various intervening parts of the inking mechanism are not shown in detail.
- 90 Referring now more particularly to the mechanism embodying the present invention, a hollow cylindrical member 20 extends across between the upright frame members 95 21 and 22 of the inking mechanism carriage. This cylindrical cross-member is shouldered at 23 and 24 to abut on finished faces on the inside of the frame members 21 and 22, and the reduced cylindrical ends fit in similarly 100 shaped apertures through the frame members and project outwardly therefrom at either side. These projecting ends of the member 20 are externally screw-threaded, and securing nuts 25 and 26 are screw-threaded thereon to bear against the exterior finished faces of the frame members to hold the member 20 in position.
- 105 Within the member 20 at either end thereof, respectively, are sleeves 27 and 28, with 110 in which is journaled a longitudinally movable rod 29, the central part 30 of this rod

being preferably of reduced diameter. The rod 29 extends outwardly at either end beyond the cylindrical supporting cross member 20, and these ends of the rod are provided with locking devices which cooperate with other devices upon the press frame.

As embodied, one end (the left hand end in Fig. 3) of rod 29 is provided with a locking member 32, having at its inner end 10 a conoidal locking or clamping part 33. The rod 29 at its opposite end (the right-hand end in Fig. 3) is of reduced diameter and is provided with a screw-thread 35. A head 36 is internally centrally screw-threaded and 15 is screwed on to the screw-thread 35. The inner end of this head 36 is provided with a conoidal locking or clamping surface 37 similar to the surface 33, and at its exterior end the head 36 has a stem 39, terminating 20 in a hand-turning-bar 40.

The cooperating locking devices are mounted on the press frame 1 and comprise arms or brackets 41 and 42. These brackets are mounted at either side on the press 25 frame, and they terminate in circular recessed bosses 43, which are internally apertured as at 44 and are laterally slotted as at 45, to receive those parts of rod 29 which project from the ends of their supporting 30 member 20. On their external faces the bosses 43 are conoidally beveled outwardly from the apertures 44 to fit or lock friction tight with the conoidal surface 33, which is fixed on one end of rod 29, and with the 35 conoidal surface 37, which is formed on the inner end of the head 36. There are usually a plurality of sets of this mechanism, one preferably located near the bottom of the inking carriage, and the other located preferably at the level of the form cylinders. 40

I also preferably make my lock fool proof. Any suitable form of mechanism for accomplishing this may be used. In the embodiment of my invention illustrated, but to 45 which my invention is not to be limited, I slot the hollow cylindrical member 20, providing it with the slots 50, 50, Fig. 3. The longitudinally movable shaft 29 is also provided with a slot 51. The sliding key 52 is mounted in these slots 50 and 51. A loose collar 53 is mounted to slide on the exterior of the hollow cylindrical member 20. The sliding key 52 is preferably provided with fingers 54, 54 to rest upon the exterior 55 surface of the loose collar 53. Between the loose collar 53 and the stationary collar 55, held to the member 20 by the set screw 56, is a coiled spring 57. This spring normally presses the loose collar 53, and the 60 sliding key 52, to the left in Fig. 3. I may also provide another fixed collar 58 held to the member 20 by the set screw 59.

This fool proof locking mechanism insures that the longitudinally movable shaft 29 will 65 be moved to the left of Fig. 3 by the action

of the spring 57, loose collar 53 and sliding key 52, and disengage the conoidal locking or clamping part 33 from the arm or bracket 42 before the attendant can disengage the conoidal locking or clamping part 37 from the other arm or bracket 41 by unscrewing the head 36. The sliding key 52 extending through the slots 50, 50 in the fixed member 20 prevents the longitudinally movable shaft 29 from rotating when the head 36 is rotated by the hand-turning bar 40. 75

The manner of operation of the hereinbefore-described mechanism is substantially as follows:

The inking carriage mechanism may be 80 considered as in the position of Fig. 2 with the holding devices in locking position, which position is also shown in Fig. 3. When it is desired to move the inking mechanism carriage away, the head 36 is rotated correspondingly and will travel backwardly away from the cooperating boss 43 after the conoidal locking or clamping part 33 has been disengaged from the arm, bracket or boss 42, in the manner previously described. 85 The inking mechanism carriage is then retracted by operating the hand wheel 13, the rod 29 during this movement of the carriage passing out laterally through the recesses 45. When the inking carriage is moved backwardly again from the position of Fig. 1 to that of Fig. 2, the rod 29 will pass in through the lateral openings 45 and come in alinement with the openings 44. 95

Rod 29 is pulled to the right in Fig. 3, when head 36 is screwed up, and the conoidal surfaces 33 and 37 are pressed into locking or clamping relation with the corresponding surfaces on the respective bosses 44, the spring 57 being then put under tension. 100 The conoidal clamping action on these various members insures absolutely centering and truing of the inking mechanism carriage with respect to the form cylinder, and insures its being held firmly and permanently 105 in this position. This action is also exactly uniform on either side of the press, and at the same time both the locking and the unlocking are effected from one side of the press by a single operation by the attendant. 110

The invention in its broader aspects is not limited to the specific mechanism shown and described and departures may be made therefrom within the scope of the accompanying claims without departing from the principles 115 of the invention and without sacrificing its chief advantages. 120

What I claim is:—

1. A printing press including in combination a form cylinder, an inking mechanism therefor, means for moving the inking mechanism into and out of operative relation with the form cylinder and means exerting a force parallel to the axis of the form cylinder for holding the inking mechanism 125 130

in operative position including a plurality of clamping devices at either side of the press and means for operating said clamping devices from one side of the press.

5 2. A printing press including in combination a form cylinder, an inking mechanism therefor, means for moving the inking mechanism into and out of operative relation with the form cylinder, means for holding the inking mechanism in operative position including clamping devices at either side of the press and extending across and movable across the press, and means for operating said clamping devices from one side of the press.

10

15

3. A printing press including in combination a form cylinder, an inking mechanism therefor, means for moving the inking mechanism into and out of operative relation with the form cylinder, means for holding the inking mechanism in operative position including a plurality of clamping devices at either side of the press and extending across and movable across the press, and means for operating said clamping devices from one side of the press.

4. A printing press including in combination a form cylinder, an inking mechanism therefor, means for moving the inking mechanism into and out of operative relation with the form cylinder, means for holding the inking mechanism in operative position including clamping devices at either side of the press and including a rod extending across and movable across the press, and means for operating said clamping devices from one side of the press.

5. A printing press including in combination a form cylinder, an inking mechanism therefor, means for moving the inking mechanism into and out of operative relation with the form cylinder, means for holding the inking mechanism in operative position including a plurality of clamping devices at either side of the press and including a rod extending across and movable across the press, and means for operating said clamping devices from one side of the press.

50 Press.
6. A printing press including in combination a form cylinder, an inking mechanism therefor, means for moving the inking mechanism into and out of operative relation with the form cylinder, means for holding the inking mechanism in operative position including clamping devices at either side of the press, and means including a screw-threaded device for operating said clamping devices from one side of the press.

55

60 7. A printing press including in combination a form cylinder, an inking mechanism therefor, means for moving the inking mechanism into and out of operative relation with the form cylinder, means for holding
65 the inking mechanism in operative position

65 the inking mechanism in operative position

including clamping devices at either side of the press and extending across the press, and means including a screw-threaded device for operating said clamping devices from one side of the press.

8. A printing press including in combination a form cylinder, an inking mechanism therefor, means for moving the inking mechanism into and out of operative relation with the form cylinder, means for holding the inking mechanism in operative position including clamping devices at either side of the press and extending across and movable across the press, and means including a screw-threaded device for operating said clamping devices from one side of the press.

9. A printing press including in combination a form cylinder, an inking mechanism therefor, means for moving the inking mechanism into and out of operative relation with the form cylinder, means for holding the inking mechanism in operative position including clamping devices at either side of the press and including a rod extending across and movable across the press, and means including a screw-threaded device for operating said clamping devices from one side of the press.

10. A printing press including in combination a form cylinder, an inking mechanism therefor, means for moving the inking mechanism into and out of operative relation with the form cylinder, means for holding the inking mechanism in operative position including clamping devices at either side of the press and including a rod extending across the press, and means including a screw-threaded device for operating said clamping devices from one side of the press. 100

11. A printing press including in combination a form cylinder, an inking mechanism therefor, means for moving the inking mechanism into and out of operative relation with the form cylinder and means for holding the inking mechanism in operative position including clamping devices at either side of the press and means for operating said clamping devices from one side of the press, and means to render said operating means fool proof. 110 115

12001 prior.

120 125 130

12. A printing press including in combination a form cylinder, an inking mechanism therefor, means for moving the inking mechanism into and out of operative relation with the form cylinder, means for holding the inking mechanism in operative position including clamping devices at either side of the press, means for operating said clamping devices from one side of the press, and means to insure that the clamping devices on one side of the press will be released momentarily before those on the other side.

13. A printing press including in com- 130

- bination a form cylinder, an inking mechanism therefor, means for moving the inking mechanism into and out of operative relation with the form cylinder, means for holding the inking mechanism in operative position including clamping devices at either side of the press, means for operating said clamping devices from one side of the press, and automatic means to insure that the clamping devices on one side of the press will be released momentarily before those on the other side.
14. A printing press including in combination a form cylinder, an inking mechanism therefor, means for moving the inking mechanism into and out of operative relation with the form cylinder, means for holding the inking mechanism in operative position including clamping devices at either side of the press, means for operating said clamping devices from one side of the press and means to insure that the clamping devices on the side opposite from the attendant will be released momentarily before those on the other side.
15. A printing press including in combination a form cylinder, an inking mechanism therefor, means for moving the inking mechanism into and out of operative relation with the form cylinder, means for holding the inking mechanism in operative position including clamping devices at either side of the press, means for operating said clamping devices from one side of the press, and automatic means to insure that the clamping devices on the side opposite from the attendant will be released momentarily before those on the other side.
16. A printing press including in combination a form cylinder, an inking mechanism therefor, means for moving the inking mechanism into and out of operative relation with the form cylinder, means for holding the inking mechanism in operative position including clamping devices at either side of the press, means for operating said clamping devices from one side of the press, and spring means to insure that the clamping devices on one side of the press will be momentarily released before those on the other side.
17. A printing press including in combination a form cylinder, an inking mechanism therefor, means for moving the inking mechanism into and out of operative relation with the form cylinder, means for holding the inking mechanism in operative position including clamping devices at either side of the press and including a rod extending across the press, means including a screw-threaded device for operating said clamping devices from one side of the press, and a sliding key mounted in the rod and means to yieldingly press it and the rod in one direction to release one of the clamping devices.
18. A printing press including in combination a press frame, a form cylinder journaled therein, an inking mechanism movable on the frame to and from the form cylinder, a plurality of cooperating centering and locking devices located on the frame and inking mechanism, one set of the locking devices being substantially at the level of the form cylinder, and another at one side thereof, said cooperating locking devices on the frame and inking mechanism being brought into engagement by said movement of the inking mechanism and cooperating together to center and lock the inking mechanism relatively to the form cylinder.
19. A printing press including a press frame, a form cylinder therein, an inking mechanism therefor movable toward and away therefrom, and cooperating centering and locking devices located on the frame and inking mechanism and including a longitudinally movable rod extending across said inking mechanism, a locking device on each end of said rod, cooperating locking devices on said press frame, resilient means for moving said rod in one direction, and threaded means for moving said rod in the opposite direction.
20. A printing press including a press frame, a form cylinder therein, an inking mechanism therefor movable toward and away therefrom, and cooperating centering and locking devices located on the frame and inking mechanism and including a longitudinally movable rod extending across said inking mechanism, a conoidal locking device fixed on one end of said rod, a rotatable, rod shifting and frame locking conoidal member on the other end of said rod, and radially slotted, internally apertured, conoidally recessed cooperating locking means on said press frame.

In testimony whereof, I have signed my name to this specification.

RALPH C. SEYMOUR.
